ABSTRACT OF THE DISCLOSURE

Epibromohydrin is reacted with 2,2-dinitro-2-fluoroethanol in a one step process to produce glycidyl 2,2-dinitro-2-fluoroethoxide (GDNFE). The conditions of the reaction prevent the formation of 1,3-bis-(2,2-dinitro-2-fluoroethoxy)-2-propanol, a by-product ordinarily formed in GDNFE preparations, which is difficult to separate from GDNFE. GDNFE is useful as a binder for explosive and propellant formulations.

BACKGROUND OF THE INVENTION

(1) Field of the invention

This invention is in the field of organic preparations. More particularly, this invention relates to the preparation of glycidyl 2,2-dinitro-2-fluoroethoxide (GDNFE) without the simultaneous formation of a by-product which is difficult to separate from GDNFE.

(2) Description of the prior art

Glycidyl 2,2-dinitro-2-fluoroethoxide (GDNFE) is known to be useful as a binder for explosive and propellant formulations. It has been prepared by a complicated, multistep process and it may be prepared by reacting epichlorohydrin with 2,2-dinitro-2-fluoroethanol (FDNE). However, the reaction of epichlorohydrin with FDNE produces, in addition to the desired product, an equal amount of 1,3-bis-(2,2-dinitro-2-fluoroethoxy)-2-propanol (BDNFEP) which is an undesirable by-product because it is difficult to separate from GDNFE. The reaction produces a mixture of GDNFE and BDNFEP according to the following equations:

Separation of GDNFE from the mixture is difficult because the chemical properties and boiling points of GDNFE and BDNFEP are very similar. Complicated separation procedures have shown that the above reaction gives about a 33% yield of GDNFE in 45 hours.

Because of the complicated separation procedures necessary to separate the by-product, BDNFEP, when epi-

2

chlorohydrin is reacted with 2,2-dinitro-2-fluoroethanol and because of the complexity of the multistep process, a sample, reasonably fast, inexpensive method for preparing GDNFE has been a subject of interest, particularly in view of the potentially great value of GDNFE as a component of explosive and propellant formulations.

SUMMARY OF THE INVENTION

It has now been unexpectedly found that there is a significant difference between the reactions of the two epihalohydrins, epibromohydrin and epichlorohydrin, with 2,2-dinitro-2-fluoroethanol. When equimolar portions of epibromohydrin and 2,2-dinitro-2-fluoroethanol are reacted for periods of from 24–70 hours at temperatures below 10° C., for example 10° C. to –10° C., and in the presence of an equimolar portion of sodium hydroxide catalyst, the reaction mixture contains only glycidyl 2,2-dinitro-2-fluoroethoxide and unreacted starting materials and no by-products are produced.

DESCRIPTION OF THE PREFERRED EMBODIMENT

Example I

25 A mixture of 107.8 g. (0.64 mole) of 91.5% pure 2,2-dinitro-2-fluoroethanol and 87.6 g. (0.64 mole) of epibromohydrin was placed in a one-liter three-necked flask fitted with a mechanical stirrer, thermometer, and dropping funnel. The mixture was cooled to 0–2° C. in an ice-bath and a solution of 25.6 g. (0.64 mole) of sodium hydroxide in 225 ml. of water was added dropwise while maintaining the temperature at 0–2° C. The reaction mixture was then stirred at 2° C. for 70 hours. Analysis of the lower organic layer by gas liquid chromatography showed the presence of 45 weight percent epibromohydrin, 16 weight percent 2,2-dinitro-2-fluoroethanol, and 37 weight percent glycidyl 2,2-dinitro-2-fluoroethoxide (GDNFE). The organic layer was separated and pumped with a high vacuum pump (0.05 mm. Hg pressure) overnight at ambient temperature to remove the volatile epibromohydrin. The residual liquid was taken up in 200 ml. of methylene chloride, washed four times with 125 ml. portions of 5% sodium hydroxide solution and 30 two times with 125 ml. portions of water. The methylene chloride solution was then dried over calcium sulfate, filtered, and concentrated under vacuum at ambient temperature to give 43.8 g. (31.3% conversion) of GDNFE. The product was a light yellow liquid $n^{25}_{\text{D}} 1.4350$, $d^{25}_{46} 1.46$. Analysis by gas liquid chromatography showed a purity of 99.6%.

40 Elemental analysis.—Calcd. for $\text{C}_4\text{H}_2\text{N}_2\text{O}_6\text{F}$ (percent): C, 28.60; H, 3.36; N, 13.33. Found (percent): C, 28.78; H, 3.29; N, 13.46.

45 50 55 The infrared spectrum was consistent with the assigned structure.

Example II

A series of comparison reactions were carried out 60 utilizing epichlorohydrin, epibromohydrin, varying reaction times, and varying reaction temperatures. When epichlorohydrin was used, 1,3-bis-(2,2-dinitro-2-fluoroethoxy)-2-propanol was always produced as a by-product. When epibromohydrin was used, but the reaction temperature was raised from 0–2° C. to 25° C., an unidentified by-product other than 1,3-bis(2,2-dinitro-2-fluoroethoxy)-2-propanol was produced. The comparison reactions are summarized in the following table. The unidentified by-product is designated as "X."

TABLE.—PROCESS STUDY ON PREPARATION OF GDNFE FROM EPIHALOHYDRIN (EHH) AND 2,2-DINITRO-2-FLUORO (FDNE)

Epihalohydrin (EHH)	Temp., °C.	Reaction time (hrs.)	Analysis of reaction mixture by gas liquid chromatography (area percent)*					
			EHH	FDNE	"X"	GDNFE	BDNFEP**	
Epichlorohydrin-----	0-2	19	39	4	0	26	30	33
	0-2	45	30	3	0	33	33	
Epibromohydrin-----	0-2	24	61	11	0	23	0	0
	0-2	48	48	12	0	32	0	
	0-2	70	45	16	0	37	0	
	25	27	33	23	13	21	0	

*Area percent is approximate equal to weight percent.

We claim:

1. The method for the preparation of glycidyl 2,2-dinitro-2-fluoroethoxide which comprises mixing and reacting at a temperature below 10° C. as equimolar mixture of epibromohydrin, 2,2-dinitro-2-fluoro-ethanol, and sodium hydroxide catalyst.

2. The method according to claim 1 wherein the mixing and reacting is conducted over a period of about 24 to 70 hours.

3. The method according to claim 1 in which glycidyl 2,2-dinitro-2-fluoroethoxide is separated from the resulting reaction mixture.

4. The method according to claim 1 wherein the temperature is from -10° C. to 10° C.

5. The method according to claim 1 wherein the temperature is from 0° C. to 2° C.
